UNITED STATES PATENT OFFICE.

SAMUEL F. MYERS, OF LOS ANGELES, CALIFORNIA.

FIREPLACE DAMPER.

1,407,351.

Specification of Letters Patent. Patented Feb. 21, 1922.

Application filed August 18, 1921. Serial No. 493,377.

To all whom it may concern:

Be it known that I, SAMUEL F. MYERS, a citizen of the United States, residing at Los Angeles, in the county of Los Angeles 5 and State of California, have invented a new and useful Fireplace Damper, of which the following is a specification.

This invention has reference to damper constructions and more particularly to 10 damper constructions employed in chimneys for regulating the draft therethrough.

The primary object of the invention is to provide a damper having means for locking the same in its positions of adjustment, 15 thus insuring the proper adjustment of the damper.

A further object of the invention is to provide an adjustable connection between the damper and its operating lever, to facilitate the installing of the damper within a 20 chimney flue.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 25 within the scope of what is claimed, without departing from the spirit of the invention.

Referring to the drawing:

Figure 1 illustrates a sectional view through a chimney showing the invention 30 as applied to the flue thereof.

Figure 2 illustrates a top plan view of the damper and its supporting frame.

Figure 3 illustrates a sectional view taken on line 3—3 of Figure 2.

40 Referring to the drawing in detail, the damper is shown as installed in a chimney flue of a fireplace, and comprises a rectangular frame having a central opening slightly larger than the sides of the rectangular damper 5, to receive the damper 5 and support the same in proper relation with the flue of the chimney.

45 The frame includes side members 6 and end members 7, the end members having inclined edges to permit the frame to be wedged between the walls of the flue so that the damper may be held within the flue against displacement, there being suitable means not shown, employed in connection with the frame for securing the frame in its proper position.

Each of the end members 7 is provided with a depressed portion which depressed portions are curved to accommodate the pintles 8 of the damper 5, and as shown, 60 one of these pintles 8 extends through the keeper 9 to secure one end of the damper to its frame, while the opposite pinte 8 is notched throughout a portion of its circumference, as at 10 to accommodate the right 65 angled end 11 of the spring member 12, which has its right angled end 13 positioned between the lugs 14, also formed on the frame.

This spring member 12 is apertured adjacent its right angled end 13 to receive the bolt 15 which passes through an opening formed in the frame, the nut 16 operating on one end of the bolt, being provided for tensioning the spring member 12 to normally hold the right angled end 11 into engagement with the notched portion of its cooperating pinte. 70

From the foregoing it is obvious that this spring member 12 has the double function 80 of preventing displacement of the pinte cooperating therewith, and at the same time restricts rotary movement thereof.

Supported on the damper proper is an elongated connecting bracket 17 provided 85 with an elongated opening 18 and a right angled end portion 19, the elongated opening 18 being provided to accommodate the bolts 20 which extend upwardly through the damper 5 and accommodate the nuts 90 21 which embrace a portion of the bracket 17 to secure the bracket to the damper 5.

This operating lever 22 has its inner extremity pivotally connected to the upper end of the right angled portion 19 of the 95 bracket 17, the opposite end of said lever 22 operating through the sleeve 23 to permit the operating lever 22 to freely move within the opening 24 provided in the chimney, to which the device is applied. 100

On the free end of the operating lever 22 is a handle 25 which handle acts as a stop to prevent the operating lever 22 from being moved to a position to cause the jamming of the damper 5.

In operation, it is obvious that if it becomes necessary to open the flue of the chimney to create a draft therethrough, it is only necessary to move the operating lever 22 to cause the damper 5 to move to a position as indicated by Figure 1 of the drawing. 110

Upon movement of the operating lever 22, the right angled end of the spring member 12 automatically assumes a position within one of the notches of the pintle thereby 5 restricting the movement of the damper 5. In order that the damper 5 will be prevented from moving below the side member 6 of the frame, a stop 26 is provided on the damper to contact with the upper surface 10 of the side member 6.

Having thus described the invention, what I claim as new is:—

1. In a damper construction, a frame, a damper supported within the frame, a relatively long bracket member adjustably connected to the damper, and an operating lever having connection with the bracket member.
2. In a damper construction, a frame, a damper having pintles, said frame having 20 bearings adapted to receive the pintles, one of said pintles having a notched portion, spring means adapted to engage within the notched portion, and means for tensioning the spring.
- 25 3. In a damper construction, a frame, a damper pivotally supported within the

frame, a connecting bracket having an elongated opening, means extending through the damper and lying within the opening for securing the bracket member to the damper, 30 and operating means having connection with the bracket for permitting the damper to be moved within its frame.

4. In a damper construction, a frame, a damper pivotally supported within the 35 frame, said damper having pintles, a pair of lugs on the frame, a spring member having right angled ends, one of said ends being positioned between the lugs, the opposite end adapted to adjustably engage with one 40 of the pintles for locking the damper in an adjusted position, means for tensioning the spring member, and means for operating the damper.

In testimony that I claim the foregoing 45 as my own, I have hereto affixed my signature in the presence of two witnesses.

SAMUEL F. MYERS.
